UNITED STATES PATENT OFFICE.

WILLIAM MACK, MARTIN A. O'TOOLE, AND JOHN F. O'TOOLE, OF SCRANTON, PENNSYLVANIA.

PUMP.

1,217,797.

Specification of Letters Patent. Patented Feb. 27, 1917.

Application filed September 14, 1914. Serial No. 861,721.

To all whom it may concern:

Be it known that we, WILLIAM MACK, MARTIN A. O'TOOLE, and JOHN F. O'TOOLE, citizens of the United States, residing at 5 Scranton, in the county of Lackawanna, State of Pennsylvania, have invented a new and useful Pump, of which the following is a specification.

The device forming the subject matter of 10 this application is a pump and one object of the present invention is to provide novel mechanism whereby the pistons which reciprocate in the pump cylinders are operatively connected with a prime mover, such as 15 a water wheel.

It is within the scope of the invention to improve generally and to enhance the utility of devices of that type to which the present invention appertains.

20 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention. 30

In the accompanying drawings:—

Figure 1 shows the invention in side elevation, parts being broken away;

Fig. 2 is a top plan;

35 Fig. 3 is an elevation delineating the opposite side of the structure from that shown in Fig. 1, one of the pump cylinders being in section; and

40 Fig. 4 is a fragmental sectional detail showing a portion of the nozzle construction.

In carrying out the invention, there is provided a supporting base 1 holding a casing 2, the casing 2 having a reduced neck 9, connected with the base 1 and constituting an outlet for the tail water. Projecting from the casing 2 is a platform 3.

50 Journaled for rotation in the casing 2 is a shaft 4 to which is secured a wheel 5 located within the casing 2 and including buckets 6. Water is delivered against the buckets 6 by nozzles 7 opening into conduits 8 in the casing, the nozzles and conduits being positioned upon the casing as may be 55 found expedient or desirable.

Located upon the outside of the casing 2 and secured to the drive shaft 4 is a main gear wheel 10 meshing into a pinion 11 journaled for rotation on a stub shaft 12 carried by and projecting from the casing 2. The 60 pinion 11 meshes into a large auxiliary gear wheel 14 journaled on a stub shaft 15 carried by the casing 2.

The auxiliary gear wheel 14 is supplied with a wrist pin 16 connected to a link 26, 65 one end of which is pivoted to a rock arm 17 the upper end of which is secured to a rock shaft 18 disposed transversely of the casing 2 and journaled in spaced bearings 19 on the top of the casing. Secured intermediate 70 its ends to the shaft 18 is a walking beam 20 to the ends of which are pivoted depending piston rods 21, the lower ends of which are mounted to rock on bearing pins 28 located in recesses 27 formed in the upper ends of 75 piston heads 22 mounted to reciprocate in cylinders 23 upheld by the platform 3. Each pump cylinder 23 is provided with an intake valve 24 and with an outlet valve 25. These valves may be of any desired construction adapted to effect the ends in view. The cylinders 23 preferably constitute parts of 80 air pumps, although obviously, some fluid other than air may be pumped if desired.

In practical operation, the water wheel 5 85 is rotated by the impact of liquid delivered against the buckets 6 through the nozzles 7 and the conduits 8. When the water wheel 5 is rotated, the shaft 4 will be rotated, motion being transmitted to the auxiliary gear 90 wheel 14 through a gear train comprising the main gear wheel 10 and the pinion 11. From the auxiliary gear wheel 14, motion will be transmitted to the rock shaft 18 through the medium of the link 26 and the 95 rock arm 17 on the shaft 18. When the shaft 18 is oscillated upon its axis, the walking beam 20 will be tilted, motion being imparted to the piston heads 22 by means of the piston rods 21. The construction is such 100 that while air is being sucked into one of the pump cylinders 23, air will be forced out of the other pump cylinder, the heads 22 operating alternatingly, to effect, respectively, the suction and discharge strokes. In this connection it is to be recalled, again, that the device in use is not confined to an air pump, but may be used to pump any fluid other than air.

The structure herein disclosed is simple 110

in form and compact. It comprises a minimum number of parts and will be found thoroughly efficient under circumstances in which a compact pumping engine is demanded.

Having thus described the invention, what is claimed is:—

In a device of the class described, a casing provided with a depending neck constituting a support for the casing and an outlet for the casing; a substantially horizontal platform secured to one side of the casing above the bottom of the casing; cylinders supported on the platform; check valves carried by the platform and coacting with the cylinders, the check valves being located below the platform, whereby the platform will constitute a protection for the check valves; pistons working in the cylinders; a walking beam; connections uniting the ends of the walking beam with the pistons, the walking beam and the connections lying immediately above the platform, whereby the platform will constitute a protection for the connections and the walking beam; a rock shaft

journaled in the casing, the walking beam being secured to one end of the rock shaft; a crank arm depending from the rock shaft and located upon the opposite side of the casing from the platform; a main shaft 30 journaled in the casing; an impact wheel on the main shaft and located within the casing; a gear train located on the same side of the casing with the crank arm and lying substantially within the perimeter of the 35 casing, the gear train including a wheel fixed to the main shaft and an auxiliary wheel journaled on the casing; and a link connecting the arm with the auxiliary wheel, the arm and the link moving within the perimeter of the casing.

In testimony that we claim the foregoing as our own, we have hereto affixed our signatures in the presence of two witnesses.

WILLIAM MACK.
